UNITED STATES PATENT OFFICE.

EDWIN S. STEVENS, OF CORNISH, MAINE; MARGARET E. STEVENS EXECUTRIX
OF SAID EDWIN S. STEVENS, DECEASED.

SASH-FASTENER.

SPECIFICATION forming part of Letters Patent No. 539,658, dated May 21, 1895.

Application filed March 28, 1894. Serial No. 505,406. (No model.)

To all whom it may concern:

Be it known that I, EDWIN S. STEVENS, a citizen of the United States of America, residing at Cornish, in the county of York and 5 State of Maine, have invented certain new and useful Improvements in Sash-Fasteners; and I do hereby declare the following to be a full, clear, and exact description of the invention, such as will enable others skilled in the art 10 to which it appertains to make and use the same.

My invention relates to improvements in sash fasteners, and especially to fasteners adapted to lock and unlock the upper and 15 lower sashes simultaneously.

It consists in a suitable case adapted to be attached to the top of the lower sash, and having mounted therein movable locking arms pivotally attached together, and adapted to 20 be slid into engagement, one with the upper sash and the other with the jamb. Said case has in the top a slot extending diagonally therein, and a guiding pin attached to said locking arms at the pivot point, and extended 25 up through said slot, and terminating in a knob for operating the arms.

It also consists in certain details of construction, which will be hereinafter more fully set forth and specifically claimed.

30 In the drawings herewith accompanying and making a part of this application, Figure 1 is a sectional view of a window with my fastener attached, taken on a horizontal line passing through the sash-fastener case when in position. Fig. 2 is a bottom plan view of the sash-fastener and case. Fig. 3 is a plan view of the same. Fig. 4 is an elevation of the knob on the top of the case. Fig. 5 is an elevation of the screw which forms the pivot of the locking-arms and which carries the knob. Fig. 6 35 is an end view of the grommet; and Fig. 7 is a sectional view of the same, showing the curved socket.

Same letters refer to like parts.

45 In said drawings *a* represents the upper sash; *b*, the lower sash; *c*, the window jamb; *d*, the bead; *e*, the cord, and *f* the facing strip.

Attached to the top of the lower sash is a suitable case *h*, one side and the end being in 50 contact with the upper sash and jamb, respectively; as seen in Fig. 1. The case *h* has

an opening *i* in the side, and an opening *j* in the end.

At points in the upper sash and in the jamb opposite said openings *i* and *j*, are made 55 curved sockets *l* and *m*. These sockets may be made in the wood, or they may have metallic keepers containing the socket inserted in the wood of the sash and jamb, as seen in sash *a* in Fig. 1.

60 Two curved locking arms are pivotally attached to each other, the pivot *n* extending upwardly through a slot *o* extending diagonally in the face of the case, and serving to guide the movement of the arms, and said pivot has attached to the top thereof a handle or knob *p*, by means of which the locking arms are operated.

The curved locking arms have substantially 70 the same curvature as the sockets or keepers in the sash and jamb, into which they are adapted to be forced in order to lock the sash.

The position of the locking arms when the sash are unlocked is shown in Fig. 3, and their position when locked is shown by dotted 75 lines in Fig. 2, and also in Fig. 1.

The keepers and locking arms being curved, the sockets may be so curved with respect to the locking arms that as they are forced into said sockets, they tend to draw the two sash 80 together, thus preventing them from rattling, and preventing the admission of cold and dust between them.

The operation of my improved sash fastener is as follows: To lock the sash, push the knob 85 forward in the slot until the ends of the locking arms enter the sockets in the sash and jamb, respectively, as seen in Fig. 1. The guiding pin of the locking arms, projecting through and being guided in the slot in the 90 case, cannot move laterally. Consequently, if the inner edge of the locking arm be curved so as to bear upon the wall of the socket when the locking arm is thrust into the socket, it tends to draw the two sash together, thus 95 making a close joint between them.

The advantages of my improved sash fastener are simplicity, cheapness and durability. Both sash are locked and unlocked simultaneously, and the locking of the sash prevents 100 the sash from rattling and makes a tight joint between them. It will also be evident

that a series of keepers may be set in the sash and jamb and thus the lower sash may be raised or the upper sash lowered to any desired position and locked.

5 Having thus described my invention and its use, I claim—

In a sash fastener the combination of a suitable case having a slot extending diagonally therein and suitable openings at the side and 10 end, with curved locking arms pivotally attached to each other at one end and with their free ends projecting loosely through said

openings and adapted to enter curved sockets in the sash and jamb and a guide pin carried by said arms and projecting through 15 said slot, substantially as and for the purposes set forth.

In testimony whereof I affix my signature in presence of two witnesses.

EDWIN S. STEVENS.
